UNITED STATES PATENT OFFICE.

WARREN V. DARLING, OF NEW YORK, N. Y.

DESIGN FOR A COMPOSITION OR BLANK BOOK COVER.

45,411.

Specification for Design.

Patented Mar. 17, 1914.

Application filed October 8, 1913. Serial No. 794,173. Term of patent 3½ years.

To all whom it may concern:

Be it known that I, WARREN V. DARLING, a citizen of the United States, residing at New York, in the county of New York and State of New York, have invented a new, original, and ornamental design for Composition or Blank Book Covers, of which the following is a specification, reference being had therein to the accompanying drawing.

The figure is a plan view of a composition or blank book cover, showing my new design.

I claim:

The ornamental design for a composition or blank book cover, as shown.

In testimony whereof I affix my signature in presence of two witnesses.

WARREN V. DARLING.

Witnesses:

E. H. HARRAD,

J. ZUSSMANN.
